UNITED STATES PATENT OFFICE.

EUGENE E. GILLETT, OF WESTERN UNION, WISCONSIN.

WEATHER-STRIP.

SPECIFICATION forming part of Letters Patent No. 295,537, dated March 25, 1884,

Application filed August 27, 1883. (No model.)

To all whom it may concern:

Be it known that I, EUGENE E. GILLETT, of Western Union, in the county of Racine, and in the State of Wisconsin, have invented certain new and useful Improvements in Door-Threshold Guards; and I do hereby declare that the following is a full, clear, and exact description thereof.

My invention relates to threshold-guards, and will be fully described hereinafter.

In the drawings, Figure 1 is a vertical section of lower part of door, with movable threshold-guard. Fig. 2 is a cross-section of same on line *x x* of Fig. 1; and Figs. 3 and 4 are also vertical sections of part of door, showing modifications.

A is the door, which has a deep groove, A', formed along the underside of its bottom rail, for the movable threshold-guard B, which is hung in the same by two links, D and E, swinging on their respective pins, *a* and *d*, and *a* and *e*, in notches *b* and *b'*, formed in upper edge of said threshold-guard B. Corresponding notches are also formed in bottom of groove of bottom rail of door, to allow of said links D and E raising the threshold-guard clear up to the bottom of groove. Elbow-link D, on the hanging side of door, has its upper end extended and bent outward to press against free end of flat spring F, which has its head fixed by screws in edge of door, said door being also provided with an irregular groove to allow said spring F to take its natural bend, (shown in dotted lines,) whereby the threshold-guard is raised from the floor.

G is a flat piece of metal fastened to the door-jamb C, and against which the movable threshold-guard is made to slide in its up-and-down motion.

B' is a cushion of india-rubber, or of any other compressible material, designed to hermetically close the door under its movable threshold-guard. In Fig. 3 is shown the arrangement of a weight, F, to raise the threshold-guard, while in Fig. 4 a spiral spring, F, is substituted for the same purpose.

As is obvious, the moment a door provided with my automatic or movable threshold-guard commences to open, the spiral or flat

spring or weight F, as the case may be, forces the threshold-guard B to swing back on its links D and E against the door-jamb, sliding up as the door continues to open, along the flat piece G on said door-jamb, the said guard gradually sliding down on said flat piece G when the door is closing, until its cushion B' is pressed against the floor at the moment the door is fully closed.

A great advantage which ensues from the use of my movable threshold-guard is that there is no necessity for using an elevated threshold-strip of wood to keep out air and dust, which was always objectionable, notably in doors between communicating rooms, where a continuous piece of carpeting went over the said strip, as the extra height of the carpet above the strip interfered with the closing of the door and was subject to undue wear at that point. Again, by reason of such strip, sweeping out a room into a hall or outdoors was rendered more difficult, and yet, if there was no provision to exclude air or dust there would be a space below the door, making the rooms cold and dirty. All this is obviated by my improved device, and such opening is always automatically and hermetically closed whenever the door is shut.

Having thus described my invention, what I claim as new, and desire to secure by Letters Patent, is—

In combination with a door provided with a longitudinal central slot or groove, A', formed in the underside of its lower edge, and a plain-surface door-jamb, the guard B, suspended by suitable links within the groove A', and with its end directly engaging the said plain jamb, and the elbow-lever D, wholly inclosed and adapted to operate in the groove of the door, substantially as set forth.

In testimony that I claim the foregoing I have hereunto set my hand, on this 16th day of May, 1883, in the presence of two witnesses.

EUGENE E. GILLETT.
